UNITED STATES PATENT OFFICE.

GEORGE F. HAUF, OF CHICAGO, ILLINOIS, ASSIGNOR TO ROBERTSON BROTHERS MANUFACTURING COMPANY, A CORPORATION OF ILLINOIS.

PIPE.

Application filed April 22, 1921. Serial No. 463,463.

To all whom it may concern:

Be it known that I, GEORGE F. HAUF, a citizen of the United States, residing at Chicago, in the county of Cook and State of Illinois, have invented certain new and useful Improvements in Pipes, of which the following is a specification.

This invention relates to pipes.

It will be explained as applied to a flexible, sectioned-pipe such as used, for example, in the conveying of grain and fodder.

In the conveyance and distribution of grain and fodder, for example in the filling of silos, it has ordinarily been the practice to employ, particularly inside of the silo, a sectioned cylindrical sheet metal pipe. The sections are usually tapered, the smaller end of one section fitting within the larger end of the adjacent section. The telescoping sections are secured together, preferably in such a manner as to allow sufficient movement between sections to render the pipe as a whole more or less flexible.

Ordinarily, heretofore, the pipe sections have been made from metal sheets of irregular outline so that, when the sheets are rolled into a tube, the sections will possess the desired taper. Either or both the upper and lower rims of the pipe sections ordinarily have been stiffened and strengthened by a bead enclosing a wire or rod core.

The production of pipe sections as heretofore manufactured is complicated and made relatively expensive by the necessity of using sheets of other than rectangular outline and the use of wire in the formation of the rim beads. The sections, which are often subject to extremely rough handling, have been found to be comparatively easily flattened or otherwise bent out of shape and when once deformed, to be extremely difficult to reshape so that the sections fit properly.

One of the objects of this invention is to provide an improved tapered pipe section.

Another object is to provide a stronger section with a given thickness of sheet.

Another object is to provide a tapered section which may be formed from a rectangular sheet.

Another object is to provide a section which may be reshaped more readily, if it should become deformed.

Another object is to provide a rim bead which gives the necessary rigidity and

strength without the use of reenforcing wires.

Another object is to provide a pipe section which is relatively simple and inexpensive to manufacture, assemble and take down.

Another object is to provide an improved method of making tapered pipe sections.

Other objects and advantages will herein-after appear.

An embodiment of the invention is illustrated in the accompanying drawing.

In the drawing—

Fig. 1 is a perspective of two interconnected pipe sections.

Fig. 2 is a plan of a sheet metal blank such as may be used in making the sections.

Fig. 3 is an elevation of a pipe section before the tapering corrugations are formed therein.

Fig. 4 is an enlarged elevation of a finished tapering pipe section.

Fig. 5 is a section on the line 5—5 of Fig. 4.

Fig. 6 is an enlarged cross section through the top rim bead, and

Fig. 7 is an enlarged elevation of a portion of a pair of sections showing how the same are flexibly coupled together.

Each pipe section 1 comprises a sheet metal tube of generally circular cross section throughout its length. The side wall of the section is provided with a series of tapering corrugations 2. The corrugations may be formed with relatively sharp apices of substantially triangular cross section as shown in the drawings or they may be formed with blunter apices giving more the effect of ripples or undulations in the surface. The corrugations gradually increase in size and depth from one end of the pipe section to the other which causes the section to taper, the smallest diameter being at that end where the corrugations are deepest.

A pipe section tapered in the foregoing manner may be formed from a sheet of simple rectangular form. The corrugations, if desired, may be produced as the forming or rolling process proceeds, the surface of the forming rollers being provided with corresponding tapered corrugations. By this process the pipe is directly formed or rolled into its proper tapered and corrugated shape.

It is preferred, however, to first form the sheet into a cylindrical tube and subsequently form the tapered corrugations to provide the desired taper of the section.

5 The corrugations may be formed in the wall of the cylindrical pipe by rolling or other suitable methods.

To provide a strengthening rim bead at the larger end of the section the edge of the sheet is turned or folded back upon the outside and then the double layer of metal thus produced is formed into two annular corrugations or projecting beads 3 and 4, as shown most clearly in Fig. 6. These beads have been found to provide excellent reinforcement for the section without the necessity of using bead cores of wire or rod as is ordinarily the practice. It has been found ordinarily sufficient to merely fold back the edge for a short distance at the smaller end of the section to give the necessary strength and rigidity.

Each pipe section is provided with a pair of holes 5 near the larger end. Near the smaller end a short length of chain 6 is attached by suitable means, such as a rivet, to opposite sides of the tube.

The free end of each chain carries an anchor 7. Anchor 7 may be formed in various ways. For example it may be made by bending a short piece of wire or rod to form a central loop or ring 8 to which a link of chain 6 is attached. The loop is made sufficiently small so that the anchor may be passed endwise through hole 5 of the next adjacent section. After being thus inserted the anchor assumes a horizontal position as shown by Figs. 4 and 7 and the sections are locked together. This coupling allows sufficient movement between adjacent sections to make the pipe as a whole flexible. By repassing the anchors endwise through the holes the sections may be disconnected readily.

47 According to the preferred method of
making the sections the sheet metal is cut
or blanked out into substantially rectangular
blanks such as shown in Fig. 2. The
50 four corners are removed as shown so that
there will not be an excessive thickness of
overlap at the ends on the longitudinal seam.
The blank is then folded along the dotted
55 lines to provide the folds for the end rims.
The blank is formed into a straight cylindrical
tube as shown in Fig. 3, and the longitudinal
edges are joined together in any
desired manner, such as by the ordinary
stove pipe lapped joint. The tube is then

corrugated with the tapering corrugations which change the cylindrical section into the desired tapering section. The annular corrugations of the upper bead are then formed in the double thickness of metal at the larger end. The anchors are then attached and the section is completed. 60 65

The tapering section thus produced is stronger and more rigid than the ordinary smooth section of the same gage or thickness of metal. The section is not so easily deformed or flattened and when flattened is more readily bent back into approximately circular shape. The double corrugated rim bead gives sufficient strength for ordinary usage and is more quickly and cheaply made than the usual wire cored bead. 70 75

By being able to make the tapering sections from substantially rectangular stock the trouble and expense of providing the customary curved edge blanks are eliminated. 80

In cases where the material, such as ensilage for example, is forced to the distributor pipe by air pressure the corrugations have an additional advantage. The deeply corrugated smaller ends of the sections fit within the smooth larger ends of adjacent sections, providing relatively large air spaces therebetween but allowing the sections to fit tightly together. The air intermixed with the material can thus readily escape between the sections and the material, being free to a more or less extent of the air, compacts more closely and a greater amount can be stored in a given space. 85 90

Having described my invention what I claim as new and desire to secure by Letters Patent, is:—

1. A method of making a pipe section which comprises folding over one edge of a sheet metal blank to form two parallel adjacent layers of metal, rolling the sheet into a tube having the two parallel layers of metal at one end, and bending outwardly both layers into a projecting reenforcing bead. 100 105

2. A pipe section comprising a sheet metal tube having one edge bent over to form a double layer of metal, a projecting bead formed in the double layer of metal and extending outwardly beyond the pipe, and tapering corrugations extending longitudinally of the tube from the base of the bead to the other end of the pipe. 110

In testimony whereof I hereunto subscribe my name.

GEORGE F. HAUF.
